(57) CLAIM

The ornamental design for a convertible cleaning kit, as shown.

DESCRIPTION

FIG. 1 is an isometric view of a convertible cleaning kit showing my new design;

FIG. 2 is a top plan view thereof;

FIG. 3 is a bottom plan view thereof;

FIG. 4 is a left side view thereof;

FIG. 5 is a right side view thereof;

FIG. 6 is a front end view thereof; and,

FIG. 7 is a rear end view thereof.

The dashed lines shown in FIGS. 1–7 represent portions of the cleaning kit and form no part of the claimed design.
